CLAIM

The ornamental design of the barricade, nestable, defensive fighting position, personnel cot bunker, as shown and described.

DESCRIPTION

FIG. 1 is a front, right, and top perspective view of a barricade, nestable, defensive fighting position, personnel cot bunker showing my new design.

FIG. 2 is a rear, left, and bottom perspective view.

FIG. 3 is an exploded top, front, and right perspective view.

FIG. 4 is an exploded bottom, rear, and left perspective view.

FIG. 5 is a collapsed top, front, and right perspective view.

FIG. 6 is a collapsed rear, bottom, and left perspective view.

FIG. 7 is an exploded pre-nestable front, top, and right perspective view; and,

FIG. 8 is an exploded pre-nestable rear, bottom, and left perspective view.
